United States Patent Office.

NICHOLAS LUMSDEN, OF SAN FRANCISCO, CALIFORNIA.

Letters Patent No. 78,385, dated May 26, 1868.

IMPROVEMENT IN BOOTS AND SHOES.

The Schedule referred to in these Letters Patent and making part of the same.

TO ALL WHOM IT MAY CONCERN:

Be it known that I, NICHOLAS LUMSDEN, of the city and county of San Francisco, State of California, have invented an Improved Machine for Making Screwed Boots and Shoes on Unplated Lasts; and I do hereby declare the following description and accompanying drawings are sufficient to enable any person skilled in the art or science to which it most nearly appertains to make and use my said invention or improvements without further invention or experiment.

The nature of my invention consists in providing an improved machine for the manufacture of screwed boots and shoes on unplated lasts, the object being, first, to construct a gauge, by which the length of the screw, and the depth to which it penetrates, shall be regulated, so that it will not be necessary to plate the last with metal to stop the screw; second, a clamp, so made as to secure the wire firmly while the screw is being cut, and yet be easily disengaged when necessary.

It also consists in a movable support for the last, which can be operated by the foot, to withdraw the last from the machine, while by means of a slide and a series of adjustable turning joints, the last is easily moved and turned into any position for receiving the screws.

Reference being had to the accompanying drawings, forming a part of this specification--

Figure 1 is a side elevation of the machine, with section showing the clamp and the withdrawing-spring.

Figure 2 is a top view.

Figure 3 is a view of the screw-plate and the cutter.

Similar letters of reference in each of the figures indicate like parts.

A is a block or frame, firmly attached to the bench, and through which the shaft B passes, supporting the gear-wheel C. This wheel turns the pinion D, which is firmly fastened to the arbor E, which is made hollow, in order to allow the wire F, of which the screws are made, to pass. The lower part of the arbor E is made tapering, having a screw cut on the outside, and is divided into four parts by slots, as shown at G. A nut, H, screws on the bottom of the arbor, and as it is turned up on the tapering screw, it compresses the sides and presses them firmly against the wire F, thus holding it in place, and preventing its turning as the screw is cut by the plate I.

When it is necessary to loosen the wire, to push it down for another screw, the pin J is pushed forward, so as to prevent the wheel C from turning. The nut H can then be loosened, and the wire moved.

Beneath the screw-plate I is a cutter, operated by the handles K K, as shown in fig. 3, and which cuts off the screw after it is driven through the sole.

The depth to which the screw penetrates is determined by means of a rod or bar, L. This bar is attached to the screw-plate, and slides perpendicularly through the block A. A nut, M, at the top, is adjusted so that, when the screw is driven as far as desired, it will be stopped by the nut M coming in contact with the block A. The nut M may be moved up or down, and thus easily regulate the length of the screw.

The last is mounted upon a standard, and is moved from side to side by a joint at N. The upper part, O, of this standard has three angular faces, $\alpha\alpha\alpha$, cut at the lower end. The screw P has one side made flat, as at α , and, when this flat side is presented to the faces $\alpha\alpha\alpha$, the part O can be moved from side to side.

By turning the screw, when either of the faces are presented, the last will be held firmly in either position. The motion forward and back about the joint R, is regulated by a nut or button, S, which engages the teeth d and thus holds the last at the desired angle.

The bottom of the standard slides along the horizontal bar T, and thus gives the last a similar movement.

A perpendicular bar, V, passes through the bar T, and has an operating-rod attached to the bottom, by which the last is removed from the screw-plate. A spiral spring, W, serves to retain the last in contact with the screw-plate, with sufficient force to make the screws enter the leather when they are turned.

A wooden cylinder, g, moving inside a hollow barrel, h, guides the apparatus, and keeps its motion in a perpendicular line. The spring W and the cylinder g are attached to the plate m, which is firmly fixed to the bench, and the rod or bar V moves through the centre.

Having thus described my invention, what I claim, and desire to secure by Letters Patent, is—
1. The regulating-guide, consisting of the sliding rod *L* and its adjustable nut *M*, together with the screw-plate *I* and the wire-holding clamp, the whole constructed and operating substantially as and for the purpose described.

2. The adjustable last-standard, constructed and operating substantially as and for the purpose described.

3. The device, consisting of the spring *W*, rod *V*, cylinder *g*, and barrel *h*, for obtaining a perpendicular motion of the last, and a pressure against the screw-plate, substantially as and for the purpose described.

In witness whereof, I have hereunto set my hand and seal,

NICHOLAS LUMSDEN. [L. S.]
